2 Sheets-Sheet 2

Fig. 4.

This technical cross-sectional diagram illustrates a bridge structure with two decks. The upper deck is supported by a central pier (10) and two side piers (11). The lower deck is supported by a central pier (10) and two side piers (11). The bridge is built on a foundation (12) consisting of four layers of rectangular blocks. The structure is labeled with various numbers: 12, 13, 14, 15, 16, 17, 18, 19, 20, 21, 22, 23, 24, 25, 26, 27, 28, 29, 30, 31, 32, and 33. The diagram shows the internal framework and support systems of the bridge, including the piers, deck beams, and foundation.

CONVEYER LOADING DEVICE

Viktor Beplate, Sydowsaue, near Stettin, Germany, assignor to North American Rayon Corporation, New York, N. Y., a corporation of Delaware

Application August 18, 1931, Serial No. 557,922
In Germany August 18, 1930

10 Claims. (Cl. 198—20)

This invention relates to a loading device for conveyers, but primarily has for its object to devise a means whereby the articles to be conveyed are transferred from one type of conveyer to another type.

In the manufacture of certain products, such as artificial silk for example, it is necessary that the articles of manufacture be given certain treatments or carried through certain manufacturing operations. In one of the steps of the process, one type of conveyer may operate in a certain way for moving the articles to be conveyed along a horizontal path, and in the next step of the process it will be found necessary to transfer the articles to a conveyer which acts to raise and lower the articles through a treating tank, dryer, etc.

It is therefore the purpose of this invention to provide a loading device which is particularly adapted for handling of skeins or yarn bodies of artificial silk. In the manufacture of artificial silk different treating steps must be carried out and certain of these steps are productive of better results if done by a dipping process, whereas others are better performed by a dipping process. This of course makes it necessary to use different types of conveyers for transporting the skeins.

It is therefore one object of the invention to provide a novel and useful transfer device between the different conveyers used whereby there will be no delay in the conveyance of the transported skeins or other articles.

Another object of this invention is to connect the two mechanisms directly to each other by supporting devices which will automatically remove a carrier rod from one mechanism and transfer it to the other.

A further object of this invention is to provide lever means secured to one mechanism, which, when a carrier rod is placed thereon, will automatically move so as to align the carrier rod with the belt or chain conveying means in the other machine which then carries the said carrier rods through the machine.

These and other objects will become more apparent from a study of the following description and attached drawings whereon:

Figure 1 is a view of a dipping tank, partially in cross section showing the novel transfer means;

Figure 2 is an end view of the dipping mechanism, the end of the tank being removed;

Figure 3 is a detailed view of the transfer mechanism before a carrier stick has been placed in position; and

Figure 4 is a similar view, but showing the op-

eration of the transfer mechanism with the carrier stick in alignment with the conveyer belt or chain.

Referring now more particularly to the drawings, there is shown a dipping tank 10 mounted on suitable supports 11. Within the tank is arranged the usual system of conveyer rollers 12 over which passes the transporting belt or chain and which supports at spaced intervals, carrier sticks 14 loaded with skeins 15. The tank is also provided with an overflow pipe 16, having the usual valve 17.

A frame or supporting structure 18 is positioned about the tank and is suitably spaced therefrom. The top 19 of the frame or supporting structure is provided with bearings 20 for shafts 21 which have secured thereto conveyer rollers 22. Lower conveyer rollers 23 are secured in position directly below the rollers 22. The conveyer is in the form of an endless belt or chain and is arranged on the rollers to carry the skein carriers through the treating liquid as is clearly shown in Figures 3 and 4, the direction of movement being indicated by the arrows.

Means are provided to transfer the skein carriers from the dipping to the dipping bath, and comprise levers 24 pivotally mounted on the fixed machine frame 25 by any suitable means such as bolts 26. Each lever is weighted at one end and is provided at the other end with a cut out portion or groove 27. Thus the levers are normally in an upright vertical position as is shown by Figure 3. A stop means 28 is also provided at the weighted end.

The conveyer belt is provided at suitable intervals with pairs of hooks 29, adapted to receive the skein carriers. These hooks consist of levers 30 pivotally secured to the conveyer chain or belt, and each having a claw like member 31 secured at one end and a counter-weight 32 at the other end.

The operation of the device is as follows:

The skein carriers 14 are led through a drip mechanism and are then placed in the grooves 27. The weight thereof causes the arms 24 to swing over into alignment with the conveyer belt. The means 33 which place the carriers in the grooves and the means which operates the conveyer are operated either from a common driving means or by independent means. In either event the two are operated in timed relation so that when the arm swings over, the claw 31 is in position to receive the skein or cake carrier. The means 33 comprises a rack which is moved in a circular path in a clockwise direction by any

suitable means (not shown). On the top half of its path it carries the skein carriers 14 up and over and rests them in the grooves 27 of the arms 24. The rack means 33 continues down and 5 back in its circular path and on rising, repeats the operation by picking up another skein carrier 14 which has been progressively moved along until it reaches the point occupied by the first 10 mentioned skein carrier 14, it then picks up the succeeding carrier 14 and deposits it in the by then vacated groove 27 of the arm 24 where it in turn is picked up by the hooks 29 on the conveyer belt. The upward movement of the chain lifts the carrier from the groove 27 and the arm 15 24 is then swung back into position by means of the weighted end to receive another carrier.

It will be readily appreciated that by the above arrangement there is provided a simple efficient and economical means of automatically transferring the skein and yarn carriers from a drip mechanism to a dip mechanism, thus obviating any handling of the product during the wet treatment.

The mechanism may be varied in many respects without departing from the terms or spirit of the invention.

Having now described the invention what is claimed is:

1. A mechanism for loading skein carrier rods 30 on a conveyer comprising a support, a plurality of members pivotally secured thereto and suspended normally in a vertical position, said members swinging into the path of said conveyer when the said rods are placed thereon, whereby the 35 rods are transferred to said conveyer upon movement thereof past the members.

2. A mechanism for transferring skein carrier rods to an endless conveyer having spaced receiving means secured thereto comprising a 40 frame, transfer members pivotally secured thereto normally suspended in a vertical position and swinging into the path of said conveyer when skein carrier rods are placed thereon, whereby the 45 said rods will be transferred to said conveyer upon movement past the transfer members.

3. A mechanism for transferring skein carrier rods to an endless conveyer means having spaced receiving means secured thereto, comprising a frame, transfer members pivotally secured thereto, each member having one end formed with a 50 recess and weighted at the other end whereby each member is normally held in vertical position, said transfer members swinging into the path of said conveyer when skein carrier rods are in said recesses, whereby the said rods will be transferred to said receiving means upon movement of the conveyer past the transferring means.

4. In a treating device for material, an endless 60 chain conveyer means for transporting the material, means for placing said material on said conveyer means comprising a frame, transfer members pivotally secured thereto and swinging into the paths of said conveyer means when said material is placed thereon whereby said material will be transferred to said conveyer means upon movement of said conveyer past the transfer members.

5. In a treating device for skeins supported on rods, a frame, an endless conveyer for transporting the rods through a tank, means for placing said rods on the conveyer comprising transfer members pivotally secured to said frame, one end

of said members being weighted to hold the said members normally in a vertical position, said members being positioned to swing into the path of said conveyer when the said rods are placed thereon, whereby said rods will be lifted from said members on the movement of said conveyer past the transfer members.

6. In a treating device for material supported on carrier rods, a frame, an endless conveyer having spaced rod receiving means for transporting the said rods, means for placing said rods on said conveyer comprising pivotally mounted transfer members secured to said frame and positioned to swing into the path of said conveyer when a rod is placed thereon whereby upon movement of said conveyer past the transfer members the rod receiving means will lift the rods from said transfer members.

7. In a treating device for material supported on carrier rods, a frame, an endless conveyer having spaced pivotally mounted rod receiving means for transporting the said rods, means for placing said rods on said conveyer comprising pivotally mounted transfer members secured to said frame and positioned to swing into the path of said conveyer when a rod is placed thereon whereby upon movement of said conveyer past the transfer members the rod receiving means will lift the rods therefrom.

8. In a treating device for material supported 105 on carrier rods, an endless conveyer having spaced rod receiving means pivotally secured thereto, for transporting the said rods through a tank, means for placing the said rods on said receiving means comprising transfer members provided at one end with recesses and being weighted at the opposite end, pivotally mounted on said frame and adapted to swing into the path of said receiving means when a material carrying rod is placed in said recesses, whereby upon 110 movement of said conveyer the rod will be lifted by said receiving means from said recesses.

9. In a treating device for material supported on carrier rods, an endless conveyer having spaced receiving means pivotally secured thereto 120 for transporting the said rods through a tank, means for placing the said rods on said receiving means comprising transfer members provided at one end with recesses and being weighted at the opposite end, pivotally mounted on said frame 125 and swinging into the path of said receiving means when a material carrying rod is placed in said recesses, whereby upon movement of said conveyer the rod will be lifted by said receiving means from said recesses, each receiving means 130 being provided with a claw to receive said rod and a counter-weight at the opposite end.

10. In a treating device for material supported on carrier rods, an endless conveyer having spaced rod receiving means pivotally secured 135 thereto for transporting the said rods through a tank, means for placing the said rods on said receiving means comprising transfer members provided at one end with recesses and being weighted at the opposite end, pivotally mounted 140 on said frame and adapted to swing into the path of said receiving means when a material carrying rod is placed in said recesses, whereby upon movement of said conveyer the rod will be lifted by said receiving means from said recesses, each 145 receiving means being provided with a recess to receive said rod.
